(57) **CLAIM**

The ornamental design for an avionics display screen with transitional icon set, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of avionics display screen with transitional icon set showing a first image in a sequence of a transitional icon set;

FIG. 2 is a front view of avionics display screen with transitional icon set showing a second image in the sequence; and,

FIG. 3 is a front view of avionics display screen with transitional icon set showing a third image in the sequence. The appearance of the transitional icon set sequentially transitions between the images shown in FIGS. 1-3. The process or period in which one image transitions to another image forms no part of the claimed design.

The wavy break lines show a symbolic break in the length of certain avionics display screen with transitional icon set. The appearance of any portion of the article beyond the break lines forms no part of the claimed design.

The broken lines illustrate perimeters of avionics display screen with transitional icon set and form no part of the claimed design.

The claimed design is directed to the collective appearance of the transitional icons shown.
